UNITED STATES PATENT OFFICE.

CHARLES BRADLEY MITCHELL, OF HAYS, TEXAS.

VALVE.

SPECIFICATION forming part of Letters Patent No. 616,796, dated December 27, 1898.

Application filed March 14, 1898. Serial No. 673,827. (No model.)

To all whom it may concern:

Be it known that I, CHARLES BRADLEY MITCHELL, a citizen of the United States, residing at Hays, in the county of Robertson 5 and State of Texas, have invented a new and useful Valve, of which the following is a specification.

My invention relates to valves, particularly of that class known as "balanced rotary valves," and has for its object to provide a simple and compact construction and arrangement of parts for efficiently controlling the flow of steam, compressed air, water, or other fluid, and especially to provide such a construction as to adapt the valve-seat and valve to be withdrawn simultaneously from the casing in which it is inclosed to expose the working parts for cleansing and repair without detaching the valve-casing from the communicating feed-pipe.

Further objects and advantages of this invention will appear in the following description, and the novel features thereof will be particularly pointed out in the appended 25 claim.

In the drawings, Figure 1 is a side view of a valve constructed in accordance with my invention. Fig. 2 is a similar view showing the outer casing in longitudinal section. Fig. 30 3 is a central longitudinal section of the entire mechanism, including the valve-seat, the valve proper being partly broken away. Fig. 4 is a transverse section on the plane indicated by the line 4 4 of Fig. 2.

35 Similar numerals of reference indicate corresponding parts in all the figures of the drawings.

1 designates a feed-pipe adapted for connection with the cylinder of an engine or other 40 receptacle to be supplied with a fluid, and connected with the feed-pipe is a cylindrical casing 2, which is preferably threaded to its place upon the feed-pipe and is axially alined therewith, the bore of the casing being of larger 45 diameter than the feed-pipe.

3 represents a tubular valve-seat of an exterior diameter which is smaller than the bore of the casing and is fitted concentrically therein, said seat being provided with a threaded 50 enlargement 4, which is engaged with a threaded terminal portion of the casing at the opposite end from said feed-pipe, the valve-seat

being provided with suitable ports 5, elongated longitudinally of the seat or parallel with the axis thereof. The valve-seat is extended beyond the threaded boss and in axial alinement with the seat, as shown at 6, and communicating laterally with the interior of this extension is a supply-pipe 7, the valve-seat extension being adapted to occupy a position outside of the casing and being fitted with a terminal cap or head 8, having a stuffing-box 9, through which extends the valve-stem 10, provided with the usual operating-lever 11 or the equivalent thereof. The valve 65 12, which is of hollow tubular construction, is carried by the stem in the valve-seat proper and is provided with lateral ports 13, adapted for registration with the ports in the valve-seat and designed to be brought into registration therewith by rotary movement of the valve. Obviously by making the ports of considerable length and narrow in proportion the opening or closing of the ports may be accomplished by a comparatively slight movement 75 of the operating-lever, whereby in case of necessity the prompt cutting off of the flow of fluid may be attained.

It will be seen from the foregoing description that by removably mounting the valve-seat in an axial position in the valve-casing and providing said seat at an intermediate point or between the valve-seat proper and its extension with an annular boss forming a cylinder-head the valve-seat may be readily 85 displaced without dismounting the valve to expose the parts for repair; also, the removal of the cap which is fitted upon the extremity of the valve-seat extension allows the axial displacement of the valve proper. Furthermore, it will be seen that this dismounting of the valve-seat and valve can be accomplished without the displacement of any other part of the mechanism with which the valve is used and that the construction of the valve 95 is such as to insure a balanced movement thereof. The inclosed portion of the valve-seat or that portion which is arranged within the casing and which is in open communication with the extension to which the inlet-pipe is connected may be made of any desired length to suit the required length of ports.

Various changes in the form, proportion, and the minor details of construction may be

resorted to without departing from the spirit or sacrificing any of the advantages of this invention.

Having described my invention, what I claim is—

In a valve mechanism, the combination of a tubular casing communicating at one end with a feed-pipe, a tubular elongated valve-seat, fitted at one end concentrically within said casing and provided at an intermediate point with an annular enlargement or head removably fitted in the opposite end of the casing from the feed-pipe, said valve-seat having an axially-alined tubular extension located outside the casing and having a lateral inlet-port and a terminal removable cap

provided with a central bearing, a rotary valve fitted in the inclosed portion of said valve-seat, and provided with axially-elongated ports for registration with corresponding ports in said seat, and a valve-stem extending axially through the valve-seat extension and the bearing in the terminal cap thereof, substantially as specified.

In testimony that I claim the foregoing as my own I have hereto affixed my signature in the presence of two witnesses.

CHARLES BRADLEY MITCHELL.
